C. A. DIES.

WRENCH.

APPLICATION FILED MAR. 27, 1919. RENEWED FEB. 8, 1921.

1,389,581.

Patented Sept. 6, 1921.

Witness:
John Enders

Inventor:
Charles A. Dies,
by Robert Burns Atty.

UNITED STATES PATENT OFFICE.

CHARLES A. DIES, OF CHICAGO, ILLINOIS, ASSIGNOR TO JOHN V. LARSON, OF CHICAGO, ILLINOIS.

WRENCH.

1,389,581.

Specification of Letters Patent. Patented Sept. 6, 1921.

Application filed March 27, 1919, Serial No. 285,600. Renewed February 8, 1921. Serial No. 443,491.

To all whom it may concern:

Be it known that I, CHARLES A. DIES, a citizen of the United States of America, and a resident of Chicago, in the county of Cook, 5 State of Illinois, have invented certain new and useful Improvements in Wrenches and the like, of which the following is a specification.

This invention relates to adjustable wrenches and like implements, and more especially to that type of the same in which a manual stress on the handle forces the pivoted jaw members against the article or work, an example of which forms the subject matter of my prior Patent No. 1,155,136, dated September 28, 1918. And the present improvement has for its various objects:

To provide a simple and efficient structural formation and combination of a guide housing and associated parts adapted to afford a durable, strong and economical construction.

To provide a simple and durable formation and association of parts whereby the adjusting screw sleeve of the implement is yieldingly held to place, and loose motion between the jaws prevented in a convenient and effective manner.

In the accompanying drawings:—

Figure 1 is a side elevation of a pipe wrench having the present improvement applied.

Fig. 2 is an enlarged fragmentary longitudinal sectional elevation of the same.

Fig. 2^x, is a detail elevation of the holding spring of the adjusting screw sleeve of the implement.

Fig. 3 is a transverse sectional elevation on line x³—x³, Fig. 2.

Fig. 4 is an elevation of the plate metal blank from which the guide housing of the implement is formed.

Like reference numerals indicate like parts in the several views.

Referring to the drawings, 1 designates the guide housing of an approximately rectangular shell form and having the detail structural formation hereinafter more fully described.

2 designates the adjustable member of the implement having a screw-threaded shank 3 of the usual rectangular or other non-circular form in cross-section and arranged for sliding movement in the guide housing 1

aforesaid. At its forward end the member 2 is formed with an angularly disposed jaw 4, the detail structure of which may vary to suit the different uses to which the implement is applied. It being the intention to provide a plurality of such adjustable heads, 60 interchangeable one with the other, and each having the required detail construction adapting it for a particular use.

5 designates an adjusting sleeve formed for convenient rotation by hand, and arranged in a recess formed in the mid-length of the upper portion of the guide housing 1 as shown, and with its bore formed with screw-threads for operative engagement with the screw-threaded shank 3 of the adjustable 70 member 2 of the implement.

6 designates the companion jaw of the implement pivotally mounted at its upper end in the guide housing 1 by a transverse pivot pin 7, adapting it for limited movement 75 toward the other jaw 4 by means hereinafter described.

8 designates the usual operating lever or arm pivoted by a transverse pin 9 in the guide housing 1 aforesaid, and having at its 80 forward end an operating toe 10 adapted for operative engagement with the forward side of the adjusting screw sleeve 5 of the implement, so that in an active movement of the lever or arm 8 the sleeve 5 and associated 85 adjustable member 2 will be forcibly moved toward the other jaw 6 of the implement, to firmly bind or engage the work or article disposed between the jaws 4 and 6. In the preferred construction shown in Figs. 1, 2 90 and 6, the lower and forward corner or heel 8' of the operating lever or arm 8 has abutment against the lower free end of the pivoted jaw 6 aforesaid, so that in the aforesaid active movement of the lever or arm 8, said 95 jaw 6 will be forcibly moved toward the companion jaw 4 simultaneously with the heretofore described movement of the jaw 4 toward the jaw 6.

The plate metal housing 1 of the present 100 structure is formed from a blank or stamping of the shape shown in Fig. 4, folded or bent to the rectangular shell structure shown in end elevation in Fig. 3 with the seam or joint 11 formed by the meeting edges, located centrally in the bottom web or wall of the structure, and with the top and bottom walls or webs preferably of an arched or seg-

mental form as shown. The housing blank or stamping in the present construction is formed as follows:

12 designates a central rectangular aperture in the body of the stamping adapted in a folded condition of the same to provide the heretofore described receiving recess for the adjusting sleeve 5 aforesaid, and one margin of said aperture 12 is formed 10 with a pair of spaced recesses 12' adapted to form abutment recesses for the herein-after described spring member by which the adjusting sleeve 5 is yieldingly held to its forward position.

13 and 14 designate pairs of orifices adapted to receive the pivot pins 7 and 9 heretofore described, when the blank or stamping is bent or folded into shape.

15 designates a pair of rectangular corner extensions adapted to form the bottom wall or web of the housing shell 1, when the stamping is bent or folded into shape. And with such construction said bottom wall is arranged at the rear end of the guide housing 1 to provide a limiting stop for the handle or lever 8 in its pivotal movement.

16 designates a pair of marginal notches adapted to provide receiving recesses for the ends of the hereinafter described transverse bridge piece or partition 16' that affords an underbearing for the shank 3 of the adjustable member 2 in its sliding movement.

16' designates the bridge piece or partition above referred to, of a segmental or arch shape as shown and with its ends having a drive fit in the notches or recesses 15 above described.

17 designates a plate metal spring member of the approximately rectangular form shown in Fig. 2^a, adapted to encircle the guide shank 3 of the adjustable member 2 and formed with forwardly disposed upper and lower portions 17' adapted to bear against the rear face of the adjusting sleeve 5 aforesaid, while near its mid-height said member 17 is formed with rearwardly curved bearing portions 17" adapted to bear and have abutment in the recesses 12' in the rear wall of the aforesaid receiving recess

in which the said adjusting sleeve 5 is arranged, as illustrated in Figs. 1, 5 and 6, and so that said spring member will exert a yieldingly stress against said adjusting sleeve 5 to hold the same against the forward wall of said receiving recess of the 55 guide housing 1 and hold said sleeve 5 and associated parts from loose movement.

Having thus fully described my said invention what I claim as new and desire to secure by Letters Patent, is:

1. In an adjustable tool of the type described, the combination of an intermediate guide housing formed with a transverse recess and provided with an operating handle, an adjustable jay member moving in said housing and provided with a revolute operating sleeve having bearing in the aforesaid housing recess, a companion jaw member attached to said housing, the aforesaid recess of the housing having abutment cavities midway the height of the same, and a spring member of a rectangular frame form encircling the adjustable jaw member and formed with upper and lower forwardly extending portions bearing against the rear 75 end of the aforesaid operating sleeve and with central rearwardly extending abutment projections having bearing in aforesaid abutment cavities of the guide housing.

2. A plate metal housing for adjustable tools comprising, an initially flat metal plate or blank formed with a central elongated rectangular aperture, the lower edge of which is formed with two recesses which form abutment cavities for a spring in the 85 finished housing, with a pair of journal orifices, and with a pair of rectangular extensions at two corners, said plate or blank being bent into a rectangular shell or housing with the various pairs of orifices and recesses in transverse alinement and with the pair of corner extensions in transverse abutting association to constitute short coating stop lugs for an operating handle.

Signed at Chicago, Illinois, this 15th day 95 of March, 1919.

CHARLES A. DIES.
